UNITED STATES PATENT OFFICE.

CHRISTY J. BAUMANN, OF PITTSBURGH, PENNSYLVANIA, ASSIGNOR TO MACBETH-EVANS GLASS COMPANY, A CORPORATION OF PENNSYLVANIA.

FURNACE CONSTRUCTION.

1,307,338.

Specification of Letters Patent. Patented June 24, 1919.

Application filed September 21, 1917. Serial No. 192,492.

To all whom it may concern:

Be it known that I, CHRISTY J. BAUMANN, a citizen of the United States, residing at Pittsburgh, in the county of Allegheny and State of Pennsylvania, have invented certain new and useful Improvements in Furnace Constructions, of which the following is a specification.

The invention relates to furnace constructions. The invention is illustrated as applied to a glass furnace but is applicable to regenerator furnaces employed for other purposes. It has for its primary objects, the provision of an improved arrangement 15 of air and gas passages and ports, whereby (1) a better mixture of gas and air is secured than has been the case with the ordinary type of construction now in use, (2) wherein increased economy in fuel consumption 20 is secured, and (3) wherein a better color in the glass produced is secured, (where the invention is used in a glass furnace) due to the better combustion of carbon which would otherwise tend to give an 25 objectionable color to the glass. One embodiment of the invention is illustrated in the accompanying drawings, wherein—

Figure 1 is a transverse section through a furnace having my improved arrangement 30 of ports and passages; Fig. 2 is a section on the line II—II of Fig. 1; and Fig. 3 is a section on the line III—III of Fig. 1.

The furnace 1 (Fig. 1) may be of any approved type, the form illustrated being 35 designed to contain a body of molten glass, and being known as a "glass melting furnace". It is customary in furnaces of this kind to provide regenerator means on the opposite sides of the furnace and alternate 40 the flow of gas and air back and forth across the furnace, a series of ports being provided along the sides of the furnace, only one set of which are shown in the construction of Fig. 1. It will be understood that the arrangements on the opposite sides of the furnace 45 are the same so that a description of one side will serve for both.

Referring, for the purpose of description, to the construction at the right-hand side of 50 the furnace, 2 and 3 are regenerator chambers filled with the usual checker work, not shown, the regenerator 2 being provided with a gas admission passage of the usual type. When the flow of gas is from the furnace to the regenerators 2 and 3, the

regenerator 2 is of course connected to the outlet stack and the gas is cut off. The invention particularly relates to the arrangement of ports and passages leading from the regenerators 2 and 3 to the furnace 1. 60

The gas passage 4 is rectangular in cross-section, as indicated in Figs. 2 and 3, and terminates in a port 5 which is short of the furnace 1. The air passage 6 from the regenerator 3 is also rectangular in cross-section, as indicated in Figs. 2 and 3, and terminates at the port 7 which constitutes the combined outlet port of both the gas and air passage. It will be understood that the passages 4 and 5 may be cross-sections other 70 than rectangular, if desired.

The air passage 6 entirely surrounds the gas passage 4 and has an inclined upper portion, as indicated at 8, such inclined upper portion serving to contract the area 75 of the air passage adjacent the end of the gas passage. The same general result could of course be secured by inclining some other part or parts of the surrounding wall so as to give what may be termed a nozzle effect. 80

The result secured by the foregoing arrangement is to provide a thorough mixing of the gas and air before the furnace is reached. This gives a better combustion than the arrangements heretofore employed, wherein 85 one inlet passage was merely placed above the other. The body of incoming air entirely surrounds the gas and the inclined upper wall 8 still further promotes the mixture since the gas and air are forced together, 90 through a restricted passage. The more perfect combustion which results from this arrangement not only gives better economy in fuel consumption, but in the case of a glass furnace, tends to secure a better color 95 in the glass of the furnace. Any unburned carbon tends to color the glass and the improved combustion incident to the arrangement of ports and passages practically eliminates any opportunity for such unconsumed carbon. Any carbon from the gas which is not completely consumed must fall 100 through the body of air beneath, and this gives an opportunity for it to burn before it strikes the glass. Other advantages incident to the construction will be apparent to those skilled in the art.

What I claim is:

1. The combination with a furnace, the wall of which is provided with a restricted 110

air and gas nozzle inlet, of a pair of regenerating chambers disposed adjacently of said wall, a gas passage extending from one of said chambers and provided with an outlet projecting inwardly toward and terminating short of said inlet, and an air conducting conduit leading from the other of said chambers to said inlet and disposed about said gas conduit to surround its outlet, the axes of said outlet and inlet being located in different planes.

2. The combination with a furnace, the wall of which is provided with a restricted air and gas nozzle inlet, of a pair of regenerating chambers disposed adjacently of said wall, a gas passage extending from one of said chambers and provided with an outlet projecting inwardly toward and terminating short of said inlet, an air conducting conduit leading from the other of said chambers to said inlet and disposed about said gas conduit to surround its outlet, the axes of said outlet and inlet being located in different planes, and the wall of said conduit being mounted upon both of said chambers and connected with the wall of the furnace about said inlet.

3. The combination with a furnace hav-

ing a nozzle inlet, of regenerating means therefor comprising adjacently disposed inner and outer chambers, a gas conduit extending upwardly from said inner chamber and provided with an outlet projecting inwardly toward and adjacent to said inlet, and an air conducting conduit leading from the outer chamber and disposed about said gas conduit, said last mentioned conduit terminating at said nozzle inlet and in advance of said outlet, the axis of said outlet being substantially co-incident with the top-line of 40 said inlet.

4. In combination with a furnace provided with an inlet passage, of a pair of associated regenerating chambers, an air admission passage leading from one of said chambers and having its outlet end provided with a wall portion downwardly inclined whereby to restrict said inlet passage, and a gas conducting conduit extending from the other of said chambers and having its 50 outlet end disposed in the outlet end of said air admission passage and confronting said downwardly inclined wall portion, the body of said conduit lying in the said air admission passage, substantially as described.

CHRISTY J. BAUMANN.
